CLAIM

The ornamental design for a pet barrier, as shown and described.

DESCRIPTION

FIG. 1 is a front, right, top perspective view of a pet barrier, showing my new design;

FIG. 2 is a rear, left, bottom perspective view thereof; FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 1;

FIG. 12 is an enlarged view of detail 12 in FIG. 1;

FIG. 13 is an enlarged view of detail 13 in FIG. 2;

FIG. 14 is an enlarged view of detail 14 in FIG. 2;

FIG. 15 is an enlarged view of detail 15 in FIG. 2;

FIG. 16 is an enlarged view of detail 16 in FIG. 2;

FIG. 17 is an enlarged view of detail 17 in FIG. 3;

FIG. 18 is an enlarged view of detail 18 in FIG. 3;

FIG. 19 is an enlarged view of detail 19 in FIG. 3;

FIG. 20 is an enlarged view of detail 20 in FIG. 3;

FIG. 21 is an enlarged view of detail 21 in FIG. 4;

FIG. 22 is an enlarged view of detail 22 in FIG. 4;

FIG. 23 is an enlarged view of detail 23 in FIG. 5;

FIG. 24 is an enlarged view of detail 24 in FIG. 5;

FIG. 25 is an enlarged view of detail 25 in FIG. 5;

FIG. 26 is an enlarged view of detail 26 in FIG. 6;

FIG. 27 is an enlarged view of detail 27 in FIG. 6;

FIG. 28 is an enlarged view of detail 28 in FIG. 6;

FIG. 29 is an enlarged view of detail 29 in FIG. 7;

FIG. 30 is an enlarged view of detail 30 in FIG. 8;

FIG. 31 is a front, right, top perspective view of its enlarged scale in an alternate configuration;

FIG. 32 is an enlarged view of detail 32 in FIG. 31;

FIG. 33 is an enlarged view of detail 33 in FIG. 31;

FIG. 34 is an enlarged view of detail 34 in FIG. 31;

FIG. 35 is a front, right, top perspective view of its reduced scale, indicating the usage environment;

FIG. 36 is an enlarged view of detail 36 in FIG. 35; and,

FIG. 37 is a front, right, top perspective view of its reduced scale, indicating another usage environment. The dash-dot-
